UNITED STATES PATENT OFFICE.

MAHLON E. LAYNE, OF HOUSTON, TEXAS, ASSIGNOR TO LAYNE & BOWLER CORPORATION, OF LOS ANGELES, CALIFORNIA, A CORPORATION OF CALIFORNIA.

SHAFT COUPLING.

Application filed January 31, 1925. Serial No. 6,156.

This invention relates to the art of rotary deep well pumps and refers particularly to the coupling of the line shafting for such deep well pumps.

5 The type of deep well pumps to which this invention relates, generally includes a pump proper including one or more rotary impellers in their housings, which pump proper is suspended by a discharge casing 10 for the pump or a discharge casing and a shaft enclosing casing within the discharge casing, which casing or casings, extend to the top of the well. This discharge casing is of considerable length and in practice is 15 made up of a number of sections which it is necessary to couple together. In practice, the rigidity of this discharge casing has been employed through the aid of spiders to reinforce the pump shaft either by providing 20 a direct bearing for the pump shaft or through supporting a shaft enclosing casing which in turn provides bearings for the shaft.

For this purpose, what is termed "spiders" 25 are commonly employed, the spiders embodying an outer sleeve or collar connected by webs to an inner sleeve or bearing for engagement with either the pump shaft or the shaft enclosing casing. As commonly 30 constructed, the pump shafting thus described has a tendency to vibrate from the top to bottom, increasing the resistance to the pumping action and increasing the wear on the several parts of the apparatus. 35 Moreover, the couplings or spiders heretofore employed for the purpose described, decrease the discharge area of the discharge casing with the result that the capacity of the pump is lowered and that the water or 40 other fluid pumped is caused to pass the spiders with an increased velocity with the resulting increase of power consumed.

It is an object of the present invention to 45 provide a rotary pump mechanism, with a line shafting which will have a substantially reduced tendency to vibrate during operation and in carrying out this object of the invention, it has been found that, by distributing the spiders of the line shaft at 50 irregular or unequal distances apart throughout the discharge column, the rhythm, or time effect, is broken, reducing vibration of

the present general type of shaft column and thereby such vibration substantially decreased, if not entirely eliminated.

55

Another object of the present invention is to provide a spider for a deep well rotary pump mechanism by which the capacity of the discharge casing may be maintained throughout the shaft column thus eliminating the increased velocity by the spider, common with the present types of such mechanism.

60

Another object of the present invention is to provide a shaft column, or a spider by 65 which a shaft column may be formed, with rounded projections at the spiders which will facilitate the installation of the apparatus.

65

A further object of the invention is to 70 provide a spider having an outer wall which will extend beyond the normal diameter of the discharge casing and is provided with grooves to permit passage of pipes, or ducts, such as oil lines, down along the exterior 75 of the column at the same time providing such column as will have surfaces projecting beyond such lines to prevent wear thereon in the installation of the apparatus.

Various other objects and advantages of 80 the present invention will appear from the following description of the preferred form or embodiment of the invention, for which purpose reference is made to the accompanying drawings, in which a preferred example 85 of a rotary pump mechanism embodying all of the features of the present invention is disclosed.

Referring to the drawings:

Figure 1 is an elevation of the upper portion of the pump mechanism.

90

Fig. 2 is an elevation of a lower portion of the assembled pump mechanism, Figures 1 and 2 being indicated as broken off along the lines *a-a*.

95

Fig. 3 is an enlarged elevation of the shaft column and is illustrated in quarter section.

100

Fig. 4 is a transverse section through the center of one of the spiders and is indicated as taken on the line 4-4, of Fig. 3.

Referring to the drawings, the rotary pump mechanism includes a rotary pump proper 2, of any preferred or customary design containing one or more impeller

2

5 housings 3 which are understood as enclosing impellers secured to a pump shaft 4. This pump shaft 4 extends vertically from the pump proper 2 to the top of the well, 10 5 where it may be driven by any suitable means, such means being indicated by the exterior housing 5 of an electric motor. The pump proper 2 is suspended from the well by its discharge casing 6 and by a casing 7 which is employed for enclosing the pump shaft 4 from the fluid passing through the casing 6. The shaft enclosing casing 7 is indicated as provided with bearing blocks 8 for supporting the pump shaft 4 against 15 weaving, the blocks 8 preferably having exterior surfaces threaded to provide a means for connecting adjacent ends of the shaft enclosing casing 7. The pump shaft 4 may, as is usual, be composed of a plurality of 20 sections held together by suitable couplings 9.

25 The discharge casing 6 of the pump is indicated as made up of a number of sections, certain of which may be joined by plain collars 10 and certain of which are joined together by spiders 11 which also serve to impart the rigidity of the shaft casing 6 to the shaft enclosing casing 7, thereby through the bearings 8 of said casing, holding the pump shaft against weaving in operation. These spiders 11 generally include a short sleeve 12 which, in the preferred embodiment of the invention, has its inner surface tapered to expand upwardly 30 35 and thus provide room for wedge members 13 which may be driven between the sleeve 12 and shaft enclosing casing 7 to firmly secure the spider thereto. The inner sleeve 12 is preferably integral with a plurality of 40 radially extending webs 14, three of which are indicated, such webs connecting at their outer ends with a coupling part or sleeve 15, the opposed ends of the inner walls of which are threaded as indicated at 16 to adjacent 45 sections of the discharge casing 6. The coupling part 15 of the spider is of greater length than the width of the webs 14 and where said webs join such coupling part the same is expanded outwardly, preferably 50 being ball form, such expansion being preferably sufficient to compensate for reduction of fluid passage in the discharge column caused by the inner sleeve 12 and webs 14 of the spider. The webs permit thinning up of 55 the material in the larger internal diameter of the spider, which makes it possible to accomplish two important things with such spiders; one, to lower the velocity of fluid passing through the spider for a given discharge rate, and second; to lower the velocity of fluid passing through the spider for a given external diameter.

60 As shown in Figure 4, the webs 14 of the spider are enlarged at their outer ends 65 18 where they join the coupling part 15 of

the spider, sufficiently to permit the formation of vertical grooves 19 in alignment with the webs 14, which grooves 19 may accommodate lines 20 passing down to the pump proper while the projecting outer surface 70 of the spider substantially encloses such lines and thus preserves the same in the well.

75 As illustrated in Figures 1 and 2, when joined together as indicated by the line a—a, it will be noted that the spiders 11 are indicated as at unequal distances apart along the shaft column. It is desired to point out that this constitutes an important feature of the invention and has been found 80 to prevent or to substantially reduce vibration of the shaft column as a whole through breaking up of the rhythm of time effect along the shaft column. It is not intended to limit this feature of the invention to placing such spiders at any particular unequal 85 distance along the shaft column or to having all of such spiders at unequal length, as various positions of the spiders and the placing at unequal distance of only some of 90 the spiders, will perform the object of the invention at least to a marked extent.

95 Among the advantages of the present invention is that by placing the spider column couplings at various distances apart, it has been found in practice that a very much less number of such spider column couplings are necessary to eliminate vibration, thereby greatly reducing the cost of the column. Moreover, by having them unequally spaced 100 and placed at greater distances apart than are the ordinary spider couplings now commonly used three advantages are obtained— (1st) a less number are required, thereby cheapening construction; (2nd) rhythmic vibration is eliminated; and (3rd) shaft threshing or hammering from one side of the bearing to the other is greatly reduced. Furthermore, by having a fewer number of 105 fixed spiders spaced at greater and unequal distances apart, slight disalignment of the discharge pipe and shaft bearing casing operates highly advantageously to the operation of the shaft column for the reason that slight disalignment of the bearings 110 occurring at greater and unequal distances apart permits the shafting to constantly contact upon one side only of the bearings, without undue friction or binding of the shafting.

115 120 This contact into the shafting upon one side only of the bearings prevents the shaft from hammering or threshing on different sides of the bearings during the period of rotation, permitting a vertical shaft to operate similar to that of a horizontal shaft which is in constant contact with one side only of the bearing. Therefore, it will be clear that 125 spider couplings placed an unequal distances along the shaft column perform the two im- 130

portant functions of (1st) breaking the rhythmic vibration of the shaft bearing above and below the unequally spaced spider couplings; and (2nd) preventing the whipping of the shafting.

It should be understood that the feature of providing grooves in the enlarged portion of the spider couplings is essential only to the preferred embodiment of the invention. Moreover, the feature of having the shaft couplings at unequal distances along the shaft columns is not necessarily limited to the use of spider couplings having an enlarged capacity or other features of the invention, nor is the feature of having the spider couplings of an enlarged capacity necessarily limited to the feature of having the spiders disposed at unequal distances along the shaft column; such features may 20 be used independently of any combination, as desired.

It is moreover to be pointed out that the feature of the enlarged capacity spider coupling is not necessarily limited to having a rounded outer portion, although the rounding of the outer portion is an advantage for the reasons described. The enlarged rounded portion of the coupling is further highly advantageous over a straight or cylindrical wall coupling in that it has a reduced tendency to distort or disrupt the inner wall of the well casing through which the pump is to pass.

While the form of the invention herein described is well suited for accomplishing the purposes of this invention, it is not intended to limit the invention to the particular description, as various modifications may be made therein without departing from the spirit of the invention. The invention is, therefore, of the scope set forth in the appended claims.

I claim:

1. A spider of the class described, comprising an inner sleeve member connected to a plurality of webs connected in turn to an outer sleeve or coupling member, said member being expanded centrally sufficient to compensate for the reduction in area caused by said inner sleeve and web. 45

2. A spider of the class described, comprising an outer coupling member having its center expanded and webs extending inwardly therefrom and supporting an interior sleeve. 50

3. A spider of the class described, comprising a ball shaped outer sleeve member, an inner sleeve member, and webs connecting said members. 55

4. In a spider of the class described, the combination of a centrally expanded member, webs of less height than the height of said expanded member extending inwardly therefrom and supporting an inner sleeve. 60

5. In a spider of the class described, the combination of an inner sleeve member, webs extending outwardly therefrom and connected to a central part of an expanded outer coupling member, said web having ends enlarged where they join such outer member, 70 and longitudinal grooves alined with said webs formed in said outer member.

6. In a rotary pump mechanism, the combination of a pump proper suspended by a discharge casing provided with spiders, a pump shaft and a shaft enclosing casing providing bearings therefor, said casing being engaged by such spiders, the spiders being expanded outwardly beyond the normal wall of the discharge casing to maintain the full area of the discharge column. 75

Signed at Houston, Texas, this fifth day of December 1924.
